UNITED STATES PATENT OFFICE.

JAMES C. SHAW, OF PHILADELPHIA, PENNSYLVANIA, ASSIGNOR TO THE WILLIAM CRAMP & SONS SHIP & ENGINE BUILDING COMPANY, A CORPORATION OF PENNSYLVANIA.

STEAM-TURBINE.

1,235,936.

Specification of Letters Patent.

Patented Aug. 7, 1917.

Application filed November 2, 1914. Serial No. 869,769.

To all whom it may concern:

Be it known that I, JAMES C. SHAW, a citizen of the United States, residing at Philadelphia, in the county of Philadelphia 5 and State of Pennsylvania, have invented certain new and useful Improvements in Steam-Turbines, of which the following is a full, clear, and exact specification.

This invention relates to steam turbines, 10 and more particularly to steam turbines for driving propellers of ships, wherein for various engineering and mechanical reasons it is desired to more or less balance the propeller thrust by opposing thereto a 15 force within the turbine derived from the steam pressure.

The present invention has for its objects 20 to simplify the construction, operation and repair of this type of marine turbine, and the invention is more especially intended for marine turbines of the impulse type.

The improvements consist generally in the elimination of wheel stages with consequent 25 elimination of diaphragms, there being but one diaphragm of the split type, the upper half of which is preferably bolted to and removable with the casing. Further improvements relate to the manner of admitting and controlling the steam to the initial nozzles, so that objectionable throttling 30 of the steam will be avoided at low powers, and also in the manner of distributing and conveying the steam through the various stages within the turbine so as to control 35 the net axial thrust. The total stages are divided between opposed drums, and the steam drop is so distributed by means of one or more compound velocity stages carried by the drums, that the net axial thrust 40 at various powers is kept within reasonably low limits. The steam is admitted intermediate the ends of the casing at one side of the diaphragm, through multiple chambers controlled by valves, and thence passes 45 through nozzles to a compound velocity stage wheel mounted on one end of the high pressure drum, to secure an initial drop, and thence passing through the drum stages wherein a further predetermined drop is 50 effected. The forward gland is subjected to this steam of reduced pressure, and thence the steam passes to and through nozzles carried by the other portion of the single dia- 55 phragm to a second compound velocity wheel stage in case of low propeller thrust,

and thence through the opposite low pressure drum stages to the condenser. A reversing turbine mounted on the same shaft is also provided, and as shown herein comprises one or more impulse nozzles, a compound velocity wheel stage carried by the reverse turbine drum, and the reverse turbine drum, leading to the condenser. It will be seen that according to this invention, the net thrust available for opposing the propeller thrust in either direction is controlled by the number of compound velocity stages, and the volume of steam required at various powers is controlled without objectionable throttling by the separate valves controlling the admission of high pressure steam to the high pressure side.

The invention is shown in two forms herein, of which,

Figure 1 represents a longitudinal section 75 of a turbine adapted for an installation where the propeller thrust is low;

Fig. 2 is a cross-section on the line 2—2 of Fig. 1;

Fig. 3 is a longitudinal section of a tur- 80 bine adapted for an installation where the propeller thrust is somewhat higher, and also shows a construction by which the steam is led from one drum to the other along the shaft, instead of externally of the casing 85 as in Figs. 1 and 2, and

Fig. 4 is a cross-section on the line 4—4 of Fig. 3.

Referring first to Fig. 1, 1 represents a main steam supply from the boiler, leading 90 into a steam belt 2, mounted on the top half of a casing 3. The steam passes directly from belt 2 to a chamber 4 without any valve and may also pass to additional chambers 5, 5, 5, 5, each controlled by valves 95 6 and hand wheels 7. These chambers 4, 5 are contained within an interior segmental ring 8 which is attached to the upper half 9 of a diaphragm, the segmental ring 8 and diaphragm part 9 being preferably bolted 100 to the upper half 3 of the casing and removable therewith. At the center the dia- 105 phragm carries a packing 10 surrounding the shaft 11. At one side of the diaphragm ring 8 is a series of nozzles 12, by which the steam is directed forwardly through the compound velocity wheel stage 13. This may have as many velocity stages as is desired for the particular installation in view, and there are also the usual stationary 110

blades. The wheel 13 is bolted to the forward drum 14, which is rigidly keyed to the shaft 1. There are also ports 15 in the compound velocity wheel 13 so that the 5 steam pressure in chamber 16 is equalized. The compound velocity wheel stage carried by the drum 14 is made of considerably greater pitch diameter than the succeeding drum stage, so that a reasonable pressure 10 drop in steam is permitted through the nozzles 12, consistent with efficiency. From chamber 16 the steam passes forwardly of the turbine through the forward drum stage 18, thence into chamber 19, where the steam 15 has of course dropped considerably from its initial pressure. This pressure in chamber 19 is that applied on the forward gland 20 and consequently, simplification and reduced loss of steam at this gland is obtained be- 20 cause of not applying the highest pressure of the steam thereto, as would be the case with steam admitted at the front head of the upper casing. Also, this makes the forward gland and the forward bearing more 25 accessible by reason of the removal of piping, and the forward bearing is maintained at a more even temperature owing to its removal from the initial high temperature of the steam.

30 At the high powers, all of the chambers 5 as well as the chamber 4 will be employed, but at low power by shutting the valves 6, only the chamber 4 will be employed, and this arrangement has the advantage of not 35 throttling the high pressure steam. Also, the nozzles 12 are preferably of different numbers of sections, each having a different total nozzle area. By employing the proper combination of one or more valve groups 40 controlling these variable nozzle sections with the nozzle section of chamber 4, which is always open, the total effective nozzle area can be varied to suit the desired power with the use of a very few valves and without 45 throttling the steam. This condition is very favorable for efficiency in this type of turbine.

From the chamber 19 in Fig. 1, the steam passes by one or more pipes 42 into a nozzle 50 chamber 21 formed in the lower half 22 of the diaphragm. This diaphragm is provided with a nozzle 23, which discharges the steam into and through the blading on the wheel 25 in a chamber 24. The second compound 55 velocity wheel stage 25 is similar in general construction to the compound velocity stage 13. Although the volume of steam has increased, the lower partial admission nozzle 23 furnishes a sufficient area to pass the 60 steam to the compound velocity stage 25. Thence the steam passes into chamber 26 and through the rear drum stage 27 to the condenser chamber 28. The rear drum 27 is carried by a head 29 which is keyed to the 65 shaft 11. The head 29 is larger than head

14. In the reverse turbine, the steam enters at 30 into a nozzle chamber 31, thence through nozzles 32 to the compound velocity rear stage 33, thence to drum stage 34 of smaller diameter, then to the condenser 70 chamber 28. 35 is the propeller of the ship, it being seen that a net pressure opposing the thrust of the propeller will be produced of relatively low value owing to the two compound velocity stages 13 and 25. The 75 net forward thrust on drum 14 will be equal to the initial pressure, less the drop in compound velocity stage 13, multiplied by the area of drum 14, less the area of drum 14 multiplied by the pressure in chamber 19. 80 The net backward thrust on drum 29 will be equal to the pressure in chamber 24 less the drop in compound velocity stage 25 multiplied by the area of drum 29, less the area of drum 29 multiplied by the condenser pres- 85 sure. The net backward pressure will be equal to the difference, and it will be seen that the use of a compound velocity stage with one or both drums, absorbing a portion of the total drop, permits a greater range 90 in the design of the drum diameters, and consequent range in blade speed, for efficient operation, than where the drum areas are solely relied upon to secure the desired net thrust. Also, this invention avoids the use 95 of excessive wheel stages in order to economically use the steam. The omission of velocity stage 25 would cause greater pressure on the forward side of drum 29 and thus increase the net thrust opposing the 100 propeller, and is specifically illustrated in Figs. 3 and 4. One or the other arrangement will be employed depending upon the conditions required by a given installation.

In Fig. 3, the steam is similarly controlled 105 by the valves 6, and passes first through the compound velocity stage and then through the forward drum into chamber 19 in the same manner as in Fig. 1. From chamber 19, however, instead of passing through the 110 pipes 42 to the chamber 24, the steam passes through passages 38 formed in a sleeve 39 keyed to the shaft 11, which sleeve also carries the drum 14. The diaphragm has a packing 40 in each instance. The lower 115 half of the diaphragm is imperforate, in Figs. 3 and 4, and the steam passes from the chamber 19 directly through passages 38 and rear chamber 24 to the rear drum stages 27. The reverse turbine is constructed sim- 120 ilarly to that of Fig. 1. In this form, it will be seen that the net thrust opposing the propeller thrust will be greater owing to the omission of velocity stage 25, but this omis- 125 sion is not essential. Nor is it essential in either form, except as stated in the appended claims, that the steam be passed from one drum to the other precisely in the respective ways shown.

Various other modifications and changes 130

in the precise arrangements shown may be made without departing from the scope of the claims.

Having thus described my invention, I declare that what I claim as new and desire to secure by Letters Patent, is:—

1. In a marine steam turbine comprising a shaft carrying a propeller and opposed pressure staged drums having a resultant opposite to the propeller thrust, a single diaphragm between said drums and a compound velocity stage carried by one of said drums adjacent to said diaphragm for effecting a drop in the effective pressure before it is applied to the drum head and initial drum stage, a live steam inlet close to said diaphragm at one side thereof and a steam conduit from the same side of said diaphragm beyond the drum on that side 20 to the other side of the diaphragm at a point close thereto.

2. In a marine steam turbine comprising a shaft carrying a propeller and opposed pressure stage drums having a resultant opposite to the propeller thrust, a single diaphragm between said drums and a compound velocity stage of larger diameter than and carried by one of said drums adjacent to said diaphragm for effecting a 30 drop in the effective pressure before it is applied to the drum head and initial drum stage, a live steam inlet close to said diaphragm at one side thereof and a steam conduit from the same side of said diaphragm beyond the drum on that side to the other side of the diaphragm at a point close thereto.

3. In a marine steam turbine installation, a shaft carrying a propeller, a plurality of pressure staged drums thereon having a resultant opposite to the propeller thrust, a diaphragm separating said drums, a steam inlet at one side thereof for supplying steam to one of said drums, means for conducting steam from the discharge end of said drum through the diaphragm to the other drum, and additional blading in advance of the stages of one of said drums for effecting a drop in the effective pressure before it is applied to the drum head and initial drum stage.

4. A marine steam turbine comprising opposed drums, a single split diaphragm, one half being chambered and having nozzles at the inlet side of one drum and cutting off the other drum, and means for passing the steam from the discharge of said first mentioned drum to the other drum, whereby intermediate wheel stages and diaphragms are eliminated.

5. A marine steam turbine comprising opposed drums, a single split diaphragm, one half being chambered and having nozzles at the inlet side of one drum and cutting off the other drum, and means for passing the

steam from the discharge of said first mentioned drum through the other part of said diaphragm to the other drum, whereby intermediate wheel stages and diaphragms are eliminated.

70

6. A marine steam turbine comprising opposed drums, a split diaphragm separating said drums, nozzles opening through one part of said diaphragm to the blading of one of said drums, a steam passage leading from said first mentioned drum to the other part of said diaphragm, and nozzles in said other part for directing the steam to the blades of said second drum.

7. A marine steam turbine comprising opposed drums, a split diaphragm separating said drums, nozzles opening through one part of said diaphragm to the blading of one of said drums, and a steam passage through another part of said diaphragm adjacent the shaft to said second drum.

8. A marine steam turbine comprising opposed drums, a split diaphragm separating said drums, impulse nozzles opening through one part of said diaphragm to the blading of one of said drums, a steam passage leading from said drum to the other part of said diaphragm, and impulse nozzles in said other part for directing the steam to the blades of said second drum.

95

9. A marine steam turbine comprising opposed drums, a split diaphragm separating said drums, impulse nozzles opening through one part of said diaphragm to the blading of one of said drums, and a steam passage through another part of said diaphragm adjacent the shaft to said second drum.

100

10. A marine steam turbine comprising a casing, an intermediate high pressure steam inlet thereto, a diaphragm dividing said casing at one side of said inlet, a drum on each side of said diaphragm, nozzles between said steam inlet and one drum, and a steam passage from the discharge end of said drum through nozzles carried by said diaphragm to said second drum.

110

11. A marine steam turbine comprising double opposed unbalanced drums, a diaphragm separating said drums, an inlet adjacent one side of said diaphragm, impulse nozzles opposite said diaphragm, a compound velocity stage beyond said nozzles mounted on one of said drums, pressure staged buckets of smaller pitch diameter carried by said drum between said velocity stage and the end of the casing, a steam passage from said first drum to said second opposed drum, and pressure staged buckets on said second drum.

115

12. A marine steam turbine comprising opposed drums, a diaphragm separating said drums, an inlet adjacent one side of said diaphragm, impulse nozzles opposite said diaphragm, a compound velocity stage beyond said nozzles, a drum carrying the

130

moving element thereof, buckets of smaller pitch diameter carried by said drum between said velocity stage and the end of the casing, a steam passage from said first drum 5 to said second opposed drum, and a velocity stage in advance of said second drum having admission nozzles in said diaphragm opposite said admission nozzles for the first drum.

10 13. A steam turbine having a casing, a belt intermediate the ends thereof, a plurality of chambers within said belt, valves controlling the inlet of steam from said belt to said casing, nozzles in each chamber, 15 a rotary element between said nozzles and the end of the casing, and a second rotary element opposing said first element actuated by steam from said first element.

14. A steam turbine comprising opposed 20 drums, a split diaphragm separating said drums, multiple nozzle chambers and valve mechanism on one side of said diaphragm for passing steam in variable quantity through variable nozzle openings in one 25 part of said diaphragm to one of said drums toward one end of the casing, a passage from the discharge end of said drum through the other part of said diaphragm to the other drum, and nozzles carried by 30 said other diaphragm part.

15. A marine steam turbine comprising opposed drums, a split diaphragm separating said drums and one half being removable with the casing, means for directly 35 supplying one of said drums with high pressure steam, and a passage from the low pressure end of said drum through the other half of said diaphragm to said other drum.

16. In combination, a turbine casing 40 divided into two parts by a single diaphragm with a steam inlet close to said diaphragm on one side thereof, a drum stage on the same side of said diaphragm, a compound velocity wheel stage carried by the drum 45 stage receiving steam from said inlet and delivering said steam to said drum stage, the steam flow through this stage being from the diaphragm toward the end of the casing, a conduit to conduct the steam from 50 that end of the casing to a point close to the diaphragm on the other side thereof, a second drum stage through which the steam passes away from the diaphragm to the opposite end of the casing, an exhaust chamber within the casing at said last mentioned 55 end thereof, and a reversing turbine in said exhaust chamber.

17. In combination, a turbine casing hav-

ing a single diaphragm across the same, said casing and said diaphragm being split along 60 a horizontal plane, a drum stage, a compound velocity wheel stage carried by the drum stage receiving steam from a point close to the diaphragm on one side thereof and conducting it to the said drum stage 65 and therethrough to the end of the casing, a conduit from that end of the casing to the other side of the diaphragm at a point close thereto, and another drum stage 70 through which the steam passes away from the diaphragm.

18. In combination, a propeller, a shaft therefor, a turbine casing around said shaft, a single diaphragm across said casing, two drum stages one on each side of said diaphragm adapted to receive the steam in succession with the flow away from the diaphragm, a compound velocity wheel stage carried by one of the drum stages and interposed close to the diaphragm so as to be 80 subject to the steam flow before it enters the associated drum stage for each said drum stage, the resultant pressures on the two drum heads being substantially equal and opposite to the propeller thrust along 85 the shaft.

19. In combination, a turbine casing with a single diaphragm across the same, a shaft within said casing passing through the diaphragm with a steam tight packing between 90 the shaft and the diaphragm, two drums on the shaft, one on each side of the diaphragm with large annular heads adjacent to the diaphragm, blades on said drums, means to admit live steam close to the diaphragm on one side thereof to flow thence through the blades on the corresponding drum toward the end of the casing, a conduit to take said steam from the end of the casing to the other side of the diaphragm at 100 a point close thereto to pass away from the diaphragm through the blades on the other drum, an exhaust chamber at the corresponding end of the casing, and a compound velocity wheel stage carried by one of the 105 drum stages close to the diaphragm and adapted to be subjected to the steam flow before it enters the blading on the corresponding drum.

In testimony whereof I affix my signature, in presence of two witnesses.

JAMES C. SHAW.
